PREPARATION OF 7-HALO-6-DEOXY-TETRACYCLINES

Joseph John Hlavka, Valley Cottage, N.Y., and James Howard Boothe, Montvale, N.J., assignors to American Cyanamid Company, New York, N.Y., a corporation of Maine
No Drawing. Filed Oct. 9, 1959, Ser. No. 845,304
11 Claims. (Cl. 260—559)

This invention relates to the preparation of 7-halo-6-deoxytetracyclines which may be represented by the following general formula:

wherein R_1 is Br, Cl or I and R_2 is H or CH_3 when R_3 is H, and R_2 is CH_3 when R_3 is OH.

The halodeoxytetracyclines of this invention may be prepared by dissolving a suitable 6-deoxytetracycline, i.e. 6-deoxytetracycline itself, 6-demethyl-6-deoxytetracycline or 5-hydroxy-6-deoxytetracycline, in a suitable solvent, such as concentrated mineral acid, i.e., hydrochloric acid, sulfuric acid, etc. and adding a halogenating agent such as an N-haloamide, i.e., N-bromosuccinimide, N-bromoacetamide, N-bromophthalimide, N-chlorosuccinimide, N-iodosuccinimide, etc. The reaction with the haloamide is preferably carried out at temperatures of from about 0° C. to about 20° C. until the reaction is complete. Alternatively, the bromination may be carried out with bromine in a strong mineral acid, i.e., HBr and in a suitable organic solvent such as a lower alkanic acid, i.e. acetic acid, propionic acid, etc., at temperatures of from about 10° C. to about 50° C. The halodeoxytetracycline so-formed is isolated from the reaction mixture by any convenient method as, for example, by precipitation with ethyl ether or the like, and the product may be purified by recrystallization from an alcohol-acetone-ether solution in a standard manner.

The halodeoxytetracyclines are biologically active and have the broad-spectrum antibacterial activity of the previously known tetracyclines. The antibacterial spectrum of certain of these compounds, representing the amount required to inhibit the growth of various typical bacteria, was determined in a standard manner by the agar dilution streak technique which is commonly used in testing new antibiotics. The minimal inhibitory concentrations, expressed in gammars per milliliter, of 7-bromo-6-demethyl-6-deoxytetracycline, 7-bromo-6-deoxytetracycline and 7-iodo-6-deoxytetracycline against various test organisms are reported in the table below. For comparison purposes the antibacterial activity of tetracycline against the same organisms is also included.

2
TABLE

	Organism	Tetra-cycline	7-Bromo-6-Deoxytetracycline	7-Bromo-6-demethyl-6-deoxytetracycline	7-Iodo-6-deoxytetracycline
5	<i>Mycobacterium ranae</i>	1	0.5	0.25	4
	<i>Mycobacterium smegmatis</i> ATCC 607	1	1	0.25	8
	<i>Staphylococcus aureus</i> 209P	2	1	1	2
	<i>Sarcina lutea</i> 1001	2	1	0.5	2
10	<i>Bacillus subtilis</i> ATCC 6633	0.5	0.25	0.25	0.5
	<i>Streptococcus pyogenes</i> C203	0.5	0.25	0.5	2
	<i>Streptococcus</i> γ No. 11	250	4	4	4
	<i>Staphylococcus albus</i> No. 69	>250	8	8	15
	<i>Streptococcus</i> β No. 80	250	4	2	4
	<i>Staphylococcus aureus</i> NY 104	2	1	1	2
15	<i>Bacillus cereus</i> No. 5	0.25	0.25	0.5	2
	<i>Pseudomonas aeruginosa</i>	15	250	31	>250
	<i>Proteus vulgaris</i> 8427	15	8	2	31
	<i>Escherichia coli</i> ATCC 9637	15	250	31	>250
	<i>Salmonella gallinarum</i>	8	250	31	>250
	<i>Escherichia coli</i> No. 22	4	15	8	62

20 The 7-iododeoxytetracycline and 7-bromodeoxytetracycline are particularly useful as diagnostic agents in the detection of cancer. The 7-iododeoxytetracycline and 7-bromodeoxytetracycline appear to concentrate in rapidly proliferating tissue such as found in tumor growths. These 25 compounds may be rendered radioactive by incorporation of iodine 131 or bromine 82 in the 7-position of the ring nucleus. These radio-labeled compounds by virtue of their gamma rays and beta particle emissions allow the detection, localization and diagnosis of neoplastic tissue.

30 The chemical methods for preparing these radio-labeled compounds are similar to those preparative methods already described for the preparation of non-radioactive compounds with the obvious exception that the radioisotope of the appropriate halogens are used.

35 The invention will be described in greater detail in conjunction with the following specific examples.

Example 1

PREPARATION OF 7-BROMO-6-DEOXYTETRACYCLINE

40 To a solution of 0.2 gram of 6-deoxytetracycline [J.A.C.S. 80, 5324 (1958)] in 10 milliliters of concentrated sulfuric acid at 0° C. is added 76 milligrams of N-bromosuccinimide. The reaction mixture is kept at 0° C. for 30 minutes, and then added slowly drop-wise to 45 200 milliliters of cold ether. A solid precipitates which is filtered and dried. The product weighs 160 milligrams. This product is crystallized from ethanol-acetone-ether solution to give 120 milligrams of purified product. This 50 product is 1.2-1.5 times as active biologically as tetracycline.

Example 2

PREPARATION OF 7-BROMO-6-DEMETHYL-6-DEOXY-TETRACYCLINE

55 A solution of 200 milligrams (0.045 m mole) of 6-demethyl-6-deoxytetracycline hydrochloride [J.A.C.S. 80, 5324 (1958)] and 80 milligrams (0.45 m mole) of N-bromosuccinimide in 5.0 milliliters of concentrated sulfuric acid is stored at ice-bath temperature for 30 minutes. 60 The reaction mixture is slowly added to 250 milliliters of cold ether and the solid that separates weighs 0.2 gram. A portion (25 milligrams) of this material is recrystallized from ethanol/ether yielding 19 milligrams of pure

10. The method of preparing 7-bromo-6-deoxytetra-cyclines of the formula:

an organic solvent at a temperature of from about 10° C. to about 50° C.
